UNITED STATES PATENT OFFICE.

AUGUST L. N. FLEMING, OF LYNDHURST, NEW JERSEY, ASSIGNOR TO MECCA MACHINERY COMPANY, OF BROOKLYN, NEW YORK. A CORPORATION OF NEW YORK.

MACHINE FOR CUTTING DISKS.

Application filed December 8, 1921. Serial No. 520,855.

To all whom it may concern:

Be it known that I, AUGUST L. N. FLEMING, a citizen of France, and resident of Lyndhurst, county of Bergen, and State 5 of New Jersey, have invented certain new and useful Improvements in Machines for Cutting Disks, of which the following is a specification.

My invention relates to disc-cutting machines and more particularly to machines for cutting disks from units or sections of cork for use as cork seals and the like, and has for its object to provide a machine of 10 novel and simple construction whereby the efficiency of the cutting operation and the productive speed are increased to a maximum extent and whereby waste of material is reduced to a minimum. Other more specific objects will appear more fully from 15 the description hereinafter and the features of novelty will be pointed out in the appended claims.

In the accompanying drawings, which illustrate an example of the invention without defining its limits, Figure 1 is a sectional elevation of the machine; Fig. 1^a is a detail sectional view; Fig. 2 is a cross-section, on an enlarged scale, on the line 2—2 of Fig. 1; Fig. 3 is a horizontal section on the line 3—3 of Fig. 1; Figs. 4 and 5 are detail sections taken, respectively, on the lines 4—4 and 5—5 of Fig. 1; Figs. 6 and 7 are vertical sections taken, respectively, on the lines 6—6 and 7—7 of Fig. 1; 20 Figs. 8 and 9 are fragmentary sections similar to Fig. 1, and Fig. 10 is a diagrammatic illustration of the cutting process.

As shown in the drawings, the machine comprises a base or table 15 supported upon 25 legs 16; a frame 17 is mounted upon said base, preferably so as to be capable of being tilted to an inoperative position with respect thereto for the purpose to be more fully described hereinafter. Thus, as illustrated, the frame 17 may be pivotally connected at 18 with the base 15 and may be rigidly locked in its operative position, for instance, by means of bolts 19 and co-operating lugs 20 formed on the base and on 30 the frame.

A flanged drum 21 is fixed upon a shaft 21^a rotatably mounted upon the frame 17 and is provided with a plurality of peripheral grooves 22, the purpose of which will 35 appear more fully hereinafter. An endless

belt 23 co-operates with the drum 21 to feed the material into the machine and passes in contact with the surface of said drum and over rollers 24 and 25 carried by shafts 26 and 27 journaled upon the frame 60 17; the belt 23 further passes over a roller 28 which is mounted upon a shaft 29 journaled in arms 30 pivotally connected with the frame 17 by means of the shaft 27, as shown in Fig. 1. Springs 31 serve to draw 65 the arms 30 toward the drum 21 whereby the one run of the belt 23 is maintained in yielding contact with said drum or with the material passing therethrough and exerts a frictional pressure thereon; bell- 70 crank levers 32 pivoted upon the shaft 26 carry a tension roller 33 and serve to maintain said belt 23 under the desired tension by the action of suitable springs 34. The belt 23 is positively driven coincidentally 75 with the periodical step-by-step movement of the drum, to be described hereinafter, by means of pinions 35 and a gear 36 which meshes with a gear 37 fixed upon the drum shaft 21^a. The drum 21, in turn, is advanced in predetermined steps by means of a ratchet wheel 38 carried by the shaft 21^a and a co-operating pawl 39 pivoted upon a lever 40 mounted to rock upon said shaft 21^a; the lever 40 is reciprocated by means 80 of a rod 41 pivotally connected at 42 with an arm 43, the latter being preferably provided with a slot 43^a in which the connection 42 is adjustable to vary the throw of the lever 40 and consequently the step-by-step feed of the drum 21. The arm 43 is carried by a shaft 44 journaled in bearing brackets 45, which depend from the base 85 15, as shown in Fig. 1. The shaft 44 further has fixed thereon an arm 46 provided with a slot 47 in which a block 48 is slidably movable. The block 48 is pivotally connected by means of a pin 49 located upon a disk 50 carried by a main driving shaft 51 journaled in suitable bearings forming 90 part of or secured to the base 15. The driving shaft receives its rotative motion in any convenient manner as, for instance, by means of a pulley 52 driven through the medium of a belt, which has been omitted 100 for the sake of clearness.

An auxiliary, stationary frame 53 is fixed upon the frame 17 and includes a plate 53^a located in juxtaposition to the drum 21 and carrying a member 54 which extends tan- 110

gentially to the drum 21 and is provided with fingers 55 extending into the grooves 22 of the drum 21, as shown in Figs. 1, 6 and 7. The member 54 may constitute an integral extension of the plate 53^a or comprise a separate element suitably connected therewith. As shown in Figs. 4 and 5, the stationary plate 53^a is provided at its opposite edges with preferably integral guide flanges 53^b, the purpose of which will appear more fully hereinafter. A plurality of feed rollers 56 carried by shafts 57 are journalled upon the auxiliary frame 53 and have their peripheries extending into recesses 58 formed in the plate 53^a, the arrangement being such that the peripheries of the feed rollers 56 lie slightly beyond the outer surface of the plate 53^a, as shown in Fig. 1. Each of the shafts 57 carries a gear 59 operatively connected through the medium of gears 60 and positively driven by means of a gear 61 which meshes with the previously mentioned gear 37 carried by the shaft 21^a. A supplemental frame 62 is pivotally connected with the arm 30 by means of the shaft 29 and depends from the latter in juxtaposition to the auxiliary frame 53, as shown in Fig. 1. The supplemental frame is formed with a plate 63 which, as shown in Fig. 5, projects between the guide flanges 53^b into close proximity to the plate 53^a and is also provided with recesses 64 for the accommodation of feed rollers 65 carried by shafts 66, the peripheries of said feed rollers 65 extending slightly beyond the plate 63. The arrangement is such that the feed rollers 65 are located in registry with the feed rollers 56 and co-operate therewith to feed the material through the machine, as will be herein-after more fully pointed out. The feed rollers 65 are positively driven by means of gears 67 located upon the shaft 66 and operatively connected through the medium of gears 68, the actual operation of the feed rollers 65 being effected through the medium of a gear 69 which meshes with one of the pinions 35, as shown in Fig. 1. The supplemental frame 62 is constructed with extensions 70 to each of which one end of springs 71 is connected, the other end of said springs being attached to hooks 72 located, for instance, upon the legs 16. In the preferred construction links 73 are connected at 74 with the extensions 70 and at 75 with arms 76 comprising integral extensions of the auxiliary frame 53; with the described arrangement the supplemental frame 62 is movably mounted by means of the arms 30 and links 73 and thus is flexible and yielding, as will be more fully set forth herein-after. The parts are so dimensioned and located that during the operation of the machine the springs 31 and 71 will exert a tension whereby the supplemental frame 62

is drawn toward the right in Fig. 1 to maintain the feed rollers 65 in proper co-operative relation with the feed rollers 56.

The machine further includes a plurality of cutting devices which, in the illustrated example, are shown in the form of tubular knives 77, 77^a and 77^b. The knives are each carried by a tubular member 78, preferably in such a manner as to be readily detachable therefrom, for instance, by being screwed into the same, as shown in Fig. 1. The members 78, in turn, are each fixed in a sleeve 79 rotatably mounted in bearings 80, which form part of a traveling head 81. The latter is slidably mounted in guideways 82 forming part of the base 15 and is reciprocated toward and away from the drum 21 by means of an arm 83 fixed upon the shaft 44 and preferably having a circular head 84 seated in a socket or recess 84^a of the traveling head 81. The knives 77, 77^a and 77^b are rotated about their axes, for instance, through the medium of a power-driven belt 85, which passes over pulleys 86, each secured upon one of the sleeves 79 and over idler pulleys 87 rotatably mounted upon extensions 88 of the traveling head 81. Ejecting rods 89 project axially through the members 78 and knives 77, 77^a and 77^b and are carried by a stationary bracket 90 suitably secured upon the base 15. For the purpose of securing the greatest economy of operation and to prevent waste of material, the knives 77, 77^a and 77^b are located above each other along an inclined line, as shown in Fig. 2, the relation being such that the cuts made by the knives will be in staggered relation to each other and with a minimum of space therebetween, as clearly shown in the diagrammatic illustration of Fig. 10. In addition to the parts so far described, the machine may include a shield 91 located between the cutting knives and the feeding mechanism and provided with apertures 92 through which the knives 77, 77^a and 77^b are arranged to project in the operation of the machine. In the preferred form the shield may be continued to include a receptacle 93 for the disks of material which are cut by the knives previously mentioned. It will be understood that the feed rollers 65 are formed at the proper points with peripheral recesses 65^a, as shown in Fig. 6, to permit the passage of the cutting knives to the material in the operation of the machine.

In describing the operation of the machine, it will be assumed that it is being used for the purpose of cutting disks of cork of the type which are customarily used as closures in combination with bottle caps and that a sheet of cork *a* is being passed through the machine, as shown in Fig. 1. While the machine is particularly adapted

for this purpose, it will be understood that it may also be used for cutting disks from other materials with equal efficiency. With the parts in the position shown in Fig. 1 of the drawings and assuming that the pulley 52 is being driven in the direction indicated by the arrow, the block 48, through the medium of the pin 49 and disk 50, will be caused to describe a circular path in the indicated direction and thereby will swing the arm 46 to the right in Fig. 1 and will correspondingly rock the shaft 44. This movement of the shaft 44 will be communicated to the arm 43 and will exert a pull upon the rod 41 whereby the lever 40 and pawl 39 will be operated toward the left in Fig. 1 in a movement of recovery. At the same time the arm 83 will be swung toward the right in Fig. 1 and will correspondingly shift the traveling head 81 in the guides 82 and thus will cause the knives 77, 77^a and 77^b to be similarly moved through the apertures 92 and the recesses 65^a of the rollers 65 into engagement with the sheet of cork *a*, which is clamped between the plates 53^a and 63 by the action of the springs 31 and 71 and thus firmly held in position. As the machine continues to operate the knives 77, 77^a and 77^b will penetrate the material *a* and will cut therefrom a series of disks, one of which will remain seated in the end of each knife. As the operation of the pulley 52 continues, the block 48 will finally swing the arm 46 toward the left in Fig. 1 and through the medium of the shaft 44 will similarly operate the lever 83 whereby the traveling head 81 and the knives 77, 77^a and 77^b will be correspondingly moved to the left or back to their normal position. This return movement of the knives being relative to the ejecting rods 89 will cause these rods to finally exert a pressure upon each of the disks of material seated in the ends of said knives whereby said disks will be ejected from the knives and deposited in the receptacle 93. It will be understood that during the reciprocating movements of the parts, the knives 77, 77^a and 77^b are continuously rotated by means of the belt 85 so that the action thereof is a true cutting action and not a punching operation whereby the disks are cut cleanly from the sheet *a* and are not punched therefrom. As a matter of fact, the rotation of the knives is continuous during the operation of the machine.

Coincidentally with the return of the traveling head 81 and the knives to their normal positions, a push will be exerted upon the rod 41 through the medium of the arm 43 whereby the pawl 39 will be caused to rotate the ratchet 38 and thereby rotatably advance the drum 21; this operation of the drum 21 carries with it the gear 37 and consequently operates the belt 23 and

also the feed rollers 56 and 65 whereby the sheet of material *a* is advanced relatively to the plates 53^a and 63 to a corresponding extent. During this movement the material is guided between the guide flanges 53^b and the plates 53^a and 63 and is prevented thereby from shifting sidewise or buckling. The described feeding of the material *a* is diagrammatically illustrated in Fig. 10 and is so arranged that a new surface of the material *a* is presented with a minimum of waste between cuts. At the completion of the feeding step the material *a* is firmly clamped in its new position by the action of the plates 53^a and 63. The previously described operation of the mechanism is then repeated, which results finally in three additional disks being cut from the material *a* and eventually deposited in the receptacle 93.

The member 54 with its fingers 55 serves to properly guide the material *a* between the plates 53^a and 63 and prevents the same from leaving its intended path. During the cutting operation the material *a* is firmly and securely clamped in position between the plates 53^a and 63 by the action of the springs 31 and 71; the auxiliary frame and supplemental frame or, specifically, the plate 53^a, flanges 53^b and plate 63 thereof serve to guide the material in a manner to hold it against buckling and lateral shifting and to clamp it in its position of rest for cutting. In some cases, instead of passing a continuous sheet of material *a* through the machine, as indicated in Fig. 1, a plurality of relatively thin sheets *a'* may be passed therethrough, as indicated in Fig. 9, or a plurality of sheets *a''* of different dimensions may be fed through, as indicated in Fig. 8. In either case, the supplemental frame 62, because of its flexible mounting, and its feed rollers 65 will adapt themselves to the conditions imposed by the type of material being fed and existing at the time to properly feed said material and to firmly fix it in position during the cutting operation; it will be understood that if the material fed through the machine is as indicated by *a'* and *a''*, a plurality of disks will be simultaneously cut by each of the knives 77, 77^a and 77^b, and will be coincidentally ejected into the receptacle 93, as previously described.

The action of the driving mechanism, that is, the block 48, connection 49 and disk 50, is such that the arm 46 and consequently the traveling head 81 with the cutting knives will be advanced in the operative direction toward the right in Fig. 1 with a comparatively slow movement, including an infinitesimal period of rest when the cutting position is reached whereby the most effective cutting action of the knives is secured; during this movement the pawl 39 describes

a movement of recovery. At the same time the movement of the arm 46 in the opposite direction is accomplished at a higher speed so that the return movement of the traveling 5 head 81 and the knives 77, 77^a and 77^b toward their normal position is quickly accomplished and at the same time the feeding movement of the material is brought about at relatively high speed. The operation of the 10 machine and its capacity is thus maintained at the highest point.

The machine is simple in construction and efficient in operation and provides a mechanism whereby disks of material, and more 15 particularly of cork, may readily be cut in large quantities with a minimum of waste and in a completely automatic manner. In order to prevent the cutting edges of the knives from becoming dulled or inoperative 20 too quickly, the plate 53^a, as shown in Fig. 1^a, may be provided with grooves or recesses 94 arranged to provide clearance for the cutting edges of the knives while in their cutting positions; in some cases, packings 94^a 25 of lead or other suitable material may be located in said recesses, as shown in Fig. 1, it being understood that, in such case, these packings are positioned in registry with the knives and are always of such a nature as to 30 exert practically no injurious action upon the cutting edges thereof.

Various modifications in the specific form shown and described may be made within the scope of the claims without departing 35 from the spirit of my invention.

I claim:

1. A disc-cutting machine comprising a drum provided with a plurality of annular grooves, means co-operating therewith to 40 feed the material, combined feeding and clamping mechanism located adjacent to said drum, a member carried by said combined feeding and clamping means and having fingers arranged to project into said 45 grooves of the drum, a plurality of cutting devices, and means for coincidentally moving said cutting devices toward and away from the material in said combined clamping and feeding means.

50 2. A disc-cutting machine comprising a drum provided with a plurality of annular grooves, means co-operating therewith to feed the material, combined feeding and clamping mechanism located adjacent to 55 said drum, a member carried by said combined feeding and clamping means and having fingers arranged to project into said grooves of the drum, a carriage movable toward and away from said combined feeding 60 and clamping means, a plurality of rotatable cutting devices located upon said carriage, and mechanism for reciprocating said carriage and for operating said drum and feeding means in predetermined steps.

65 3. A disc-cutting machine comprising a

drum, an endless belt co-operating therewith to feed the material in a curved path, a stationary auxiliary frame, feed rollers rotatably mounted thereon, a movable supplemental frame, feed rollers thereon co-operating with the first-named feed rollers to feed the material in a linear direction and to clamp it against movement, gearing operatively connecting all of said feed rollers and said endless belt with said drum, a plurality of cutting devices movable toward and away from said material, and mechanism for reciprocating said cutting devices and for operating said drum, endless belt and feed rollers in predetermined steps. 70 75 80

4. A disc-cutting machine comprising a drum, an endless belt co-operating therewith to feed the material in a curved path, a stationary, auxiliary frame, feed rollers rotatably mounted thereon, a movable supplemental frame, feed rollers thereon co-operating with the first-named feed rollers to feed the material in a linear direction and to clamp it against movement, gearing operatively connecting all of said feed rollers and said endless belt with said drum, a traveling head slidable toward and away from the material, tubular cutting members located upon said traveling head at spaced intervals along an inclined line, means whereby cutting knives are rotated about their axes and mechanism for reciprocating said traveling head and for operating said drum, belt and feeding rollers in predetermined steps. 85 90 95 100

5. A disc-cutting machine comprising a support, a frame pivotally mounted upon said support, a drum rotatably mounted upon said frame, an endless belt mounted upon said frame and co-operating with said drum to feed the material, an auxiliary frame connected with said first-named frame, a supplemental frame connected with said first-named frame, a plurality of feed rollers on said auxiliary and supplemental frames co-operating to feed the material and to clamp the same against movement, a spring for drawing the supplemental frame toward the auxiliary frame, gearing connecting said feed rollers and said endless belt with said drum, a pawl and ratchet mechanism connected with said drum, a rock shaft connected with said pawl and ratchet mechanism for actuating the latter in predetermined steps, a traveling head slidable toward and away from the supplemental frame, a plurality of tubular cutting members rotatably mounted upon said traveling head in spaced relation along an inclined line, means for rotating said cutting members about their axes, an arm mounted upon said rock shaft and connected with said traveling head, a slotted arm on said rock shaft, mechanism for oscillating said arm whereby said traveling head is reciprocated 105 110 115 120 125 130

and said pawl and ratchet mechanism is actuated, and stationary ejecting rods for ejecting the cut disks from said cylindrical cutting devices.

6. A disc cutting machine comprising a feed drum, an endless belt co-operating with said drum to feed the material in a curved path, a fixed support, feed rollers thereon, a movable support, co-operating feed rollers thereon for feeding the material in a straight path and for automatically yielding and adjusting themselves in accordance with the material being fed and means for cutting disks from said material.

10. 7. A disc cutting machine comprising a feed drum, an endless belt co-operating with said drum to feed the material in a curved path, a fixed guide member, feed rollers thereon, an adjustable guide member, feed rollers thereon for feeding the material in a straight path and for automatically adjusting themselves in conformity with the material being fed, means for intermittently driving said feed rollers, belt and drum, and 20 springs whereby said rollers are caused to grip said material.

25. 8. In a disc cutting machine, a stationary plate, a plurality of feed rollers mounted

thereon, a supplemental plate pivotably movable and provided with openings, a plurality of feed rollers on said supplemental plate provided with grooves in registry with said openings and co-operating with said first-named feed rollers to feed the material, a plurality of rotary cutters, means for adjusting said cutters through the spaces between the grooves of adjacent feed rollers and through said openings to cut disks from said material and means whereby said plates are caused to clamp said material during the cutting operation.

30. 9. In a disc cutting machine, a stationary plate, a plurality of feed rollers mounted thereon, a supplemental plate pivotally movable, a plurality of feed rollers on said supplemental plate co-operating with said first-named feed rollers to feed the material, means for cutting disks from said material and springs whereby said supplemental plate is permitted to automatically 45 adjust its feed rollers to the material and to clamp the latter during the cutting operation.

35. In testimony whereof I have hereunto set my hand.

AUGUST L. N. FLEMING.
